UNITED STATES PATENT OFFICE.

JOSEPH BARRAJA-FRAUENFELDER, OF BRIDGEPORT, CONNECTICUT, ASSIGNOR TO THE LAKE TORPEDO BOAT COMPANY OF MAINE, OF BRIDGEPORT, CONNECTICUT, A CORPORATION OF MAINE.

ATTACHMENT FOR SUBMARINE BOATS.

1,142,768.

Specification of Letters Patent.

Patented June 8, 1915.

Application filed August 29, 1914. Serial No. 859,206.

To all whom it may concern:

Be it known that I, JOSEPH BARRAJA-FRAUENFELDER, a citizen of the United States, residing at Bridgeport, in the county 5 of Fairfield and State of Connecticut, have invented certain new and useful Improvements in Attachments for Submarine Boats, of which the following is a specification.

The object of the invention is to provide 10 an attachment for submarine boats which will serve the double purpose of providing a marker-buoy to designate the location of a disabled sunken submarine boat, and to provide means for attaching a hoisting cable 15 to the disabled craft without the services of divers, so that the disabled craft may be either raised to the surface or hauled over the water-bed into shallow water where the rescue of the crew and salvage operations 20 may be more conveniently and expeditiously carried out.

The invention consists in providing a 25 marker-buoy which is firmly locked in a cylindrical receptacle built upon or secured to the boat, said marker-buoy having messenger-lines detachably connected thereto which are coiled in recesses or pockets formed in the receptacle and held in place by the marker-buoy, the marker-buoy being 30 seated water-tight upon the receptacle to prevent water from entering said recesses or pockets in the event of the deck of the boat being washed by heavy seas or when the boat is submerged under normal conditions, whereby the messenger-line is kept 35 dry and prevented from being damaged by the water.

The invention further consists in certain 40 peculiar features of construction, combination, and arrangement of parts as will be hereinafter fully described and then claimed.

In the drawings illustrating the invention, in the several figures of which like 45 parts are similarly designated, Figure 1 is a diagrammatic view illustrating the application of the invention. Fig. 2 is a vertical longitudinal section of a portion of the hull of a submarine boat and the superstructure 50 arranged thereon, and illustrating the marker-buoy in position on its receptacle. Fig. 3 is a vertical longitudinal section of the receptacle showing the marker-buoy in

elevation and detached from the receptacle. Fig. 4 is a side elevation of the anchor-bolt 55 used in connection with the invention for attaching a hoisting cable to the boat. Fig. 5 is an inverted plan view of the marker-buoy. Fig. 6 is a horizontal section of the receptacle drawn on the line *a—a* of Fig. 60 3. Fig. 7 is a vertical transverse section drawn on the line *b—b* of Fig. 3, illustrating the anchor-bolt in locked position in the receptacle.

1 designates a submarine boat having a 65 superstructure 2 built thereon in which, preferably adjacent to the ends of the boat are wells 3, the walls of the wells being flared outwardly at their upper ends as at 4. Within each well is a cylindrical recep- 70 tacle 5 for the marker-buoy 6 and as the receptacles and marker-buoys are exactly alike in construction only one will be described. Each receptacle is cylindrical in cross-section and formed at its lower end 75 with a flange 7 which is riveted or otherwise rigidly connected to the hull plating 8 of the boat, and intermediate its ends is provided with a horizontal partition 9 from which extends a tubular sleeve 10, having its 80 upper end flush with the top of the wall of the receptacle providing an annular recess 11 and a central socket 12, which is of larger diameter intermediate its upper and lower ends to provide a shoulder 12' de- 85 signed to be engaged by spring actuated pawls carried by an anchor-bolt as will be hereinafter more fully described. Within the lower end of the socket 12 is a short sleeve 13 providing an annular recess or 90 pocket 14 in the lower end of the socket 12 and in which is wound one section 15 of a messenger-line carried by the marker-buoy 6, the opposite end, or section 16 of the messenger-line being wound around the 95 sleeve 10 in the lower end of the annular recess 11. Extending from the lower side of the transverse partition 9 are ears 17 in which is journaled a sheave 18, around which the messenger-line operates. As 100 shown in Figs. 2 and 3 one end of the messenger line extends through an opening 19 in the partition 9 which leads into the recess 11, while the other end passes up through the short sleeve 13, said sleeve be- 105 ing provided with a slot 20, whereby the

messenger-line may be coiled in the pocket 14 without extending the line entirely through the sleeve as illustrated in Fig. 2.

21 designates a guard band arranged partly around the sheave to prevent the messenger-line from jumping the sheave as will be readily understood.

The marker-buoy 6 is hollow and may be a metal casting or constructed of sheet metal as desired, and is formed with a head 22 having a convex top and tapering side walls which are inclined inwardly from their upper toward their lower ends, the angle of the walls corresponding to the angle of the upper end 4 of the well 3, so that it will snugly fit within the well when locked in position upon the receptacle. From the lower side of the head 22 of the marker-buoy extends a double-wall cylindrical sleeve 23 which is designed to fit the annular recess 11, and a hollow central section 24 which is designed to snugly fit the upper end of the socket 12, the said sleeve 23 and hollow section 24 being of such a length that when in position in the receptacle the lower ends thereof will rest upon the coiled messenger-line as shown in Fig. 2, to hold the coils in position and prevent them from being tangled. The end of the section 15 of the messenger-line is connected to an eye-bolt held in a recess 25 formed in the lower end of the said hollow section 24, and the end of the section 16 of said messenger-line is connected to an eye-bolt held in a recess 26 formed in the lower end of the sleeve 23. The lower side of the head 22 is formed with annular recesses or sockets to receive packing rings 27 of suitable material which engage the upper ends of the outer wall of the receptacle 5 and the top of the sleeve 10, respectively.

In order to securely lock the marker-buoy in position upon the receptacle and to press the packing rings firmly into engagement with the upper ends of the wall of the receptacle and the sleeve to provide watertight joints, I provide the following arrangement:—Pivoted in ears 28 extending outwardly from the flared end 4 of the well 3, below the deck 2' of the superstructure, are pawls 29 having their free ends operating through slots 30 formed in the section 4 of the well. The opposite ends of the pawls are connected to the upper ends of connecting rods 31, the lower ends of which are connected through universal connections 32, with the upper ends of bolts 33 which extend through stuffing boxes 34 secured to the hull plating 8 of the boat and said bolts have their inner ends threaded. Upon the threaded ends of the bolts operate hand wheels 35, the hubs of which bear against brackets 37 and the inner ends of the stuffing boxes 34, so that as the wheels are rotated the rods 33 and their connections will be

raised and lowered to thus operate the pawls 29. By this construction it will be understood, that, when the wheels are rotated in one direction the connecting rods will be forced upwardly to thus cause the free ends of the pawls to engage the top of the marker-buoy and thus not only lock it in position, but also force the packing rings 27 into engagement with the upper end of the receptacle and the sleeve 10. When the direction of rotation of the wheels is reversed, the pawls 29 are released from engagement with the marker-buoy, thus permitting its removal when the boat is on the surface of the water and also permitting it to be floated to the surface when the boat is submerged.

The invention so far as described follows out the general principle of other marker-buoys proposed for use in connection with submarine boats, and it will be understood, that should the buoy be released when the boat is submerged it will rise to and float upon the surface, the lengths 15 and 16 of the messenger-line being automatically uncoiled as the buoy rises to the surface. However, in connection with the invention as described I employ means for attaching hoisting cables to the receptacle, to lift the boat to the surface or to drag it over the water-bed into shallow waters where salvage operations may be conveniently carried on. As stated, the socket 12 is formed with a shoulder 12' designed to be engaged by spring actuated pawls carried at the lower end of an anchor-bolt carried by a hoisting cable shown in Figs. 4 and 7.

40 designates the anchor-bolt provided with vertical oppositely disposed slots 41 in which operate spring actuated pawls 42, pivotally held at their lower ends upon bolts held in the lower ends of the slots.

43 designates a hoisting cable to which the anchor-bolts are connected.

The operation of the invention is as follows:—Assuming a boat having my improvement installed thereon to have been sunk, and unable to rise to the surface through its own resources. The marker-buoys are first released and allowed to float to the surface and when picked up by a surface craft the end of the section 15 of the line is detached from the buoy and connected to the anchor-bolt, preferably as shown in Fig. 7, the end of the length 16 of the line is then detached and as the hoisting-cable is lowered the end 16 of the line is drawn upwardly to thus guide and pull the anchor-bolt into the socket 12, it being understood that when the lower end of the anchor-bolt enters the said socket 12 the pawls 42 will be pushed inwardly into their recesses against the tension of their springs until the upper ends of said pawls pass the shoulder 12' of the sleeve 10 when the

5 springs will force them outwardly and under the shoulder 12' thus locking the anchor-bolt to the receptacle, after which, by suitable hoisting apparatus, the sunken
5 craft is either drawn to the surface of the water or hauled over the water-bed into shallow waters as previously described.

It will thus be seen that the invention is
10 exceedingly simple in construction and that
10 a hoisting-line or lines may be readily connected to a disabled sunken submarine boat without the employment of divers, irrespective of the depth of the water in which the boat may have been sunk, and will be found
15 particularly advantageous in recovering a disabled craft when it has been sunk beyond the working depth of divers. It will, of course, be understood, that while not shown, suitable telephone wires may be carried by
20 the marker-buoy whereby communication between a surface boat and the sunken boat may be established. As this feature forms no part of the present invention I have not thought it necessary to describe it in detail
25 nor to illustrate it.

What I claim is:—

1. The combination with a submarine boat provided with a well, of a receptacle arranged in said well rigidly connected to the
30 hull of the boat, said receptacle having an annular recess and a centrally disposed socket, a shoulder formed on the wall of said socket, a marker-buoy having a sleeve adapted to fit said annular recess and a central section adapted to fit within said socket, a messenger-line connected to said marker-buoy, said messenger-line being housed in the lower end of said recess and said socket when the marker-buoy is in position upon said receptacle, a sheave around which said line operates, means for locking said marker-buoy upon said receptacle, a hoisting-cable having an anchor-bolt adapted to fit said socket when the marker-buoy is detached from said
35 receptacle, and spring actuated pawls carried by said anchor-bolt adapted to engage said shoulder, said anchor-bolt being drawn into said socket by said messenger-line.

2. The combination with a submarine boat
50 having a superstructure provided with a well, of a receptacle arranged in said well rigidly connected to the hull of the boat, said receptacle having an annular recess and a centrally disposed socket, a shoulder formed on the wall of said socket, a marker-buoy having a sleeve adapted to fit said annular recess and a central section adapted to fit within said socket, a messenger-line connected to said marker-buoy, said messenger-line being housed in the lower end of said annular recess and said socket when the marker-buoy is in position upon said receptacle, a sheave around which said line operates, means for locking said marker-buoy upon said receptacle, a hoisting-cable having
55

an anchor-bolt adapted to fit said socket when the marker-buoy is detached from said receptacle, and spring actuated pawls carried by said anchor-bolt adapted to engage said shoulder, said anchor-bolt being drawn into said socket by said messenger-line, substantially as and for the purpose specified.

3. An attachment for submarine boats, comprising a cylindrical receptacle rigidly connected to the hull of the boat, a horizontal partition arranged in the receptacle, a centrally disposed tubular sleeve extending upwardly from said partition providing an annular recess and a central socket within said receptacle, a shoulder formed upon the wall of said sleeve, a marker-buoy having a sleeve adapted to fit said annular recess and a central section adapted to fit within the sleeve of the said receptacle, packing rings carried by said marker-buoy adapted to engage the top of the wall of said receptacle and the top of the sleeve thereof to provide water-tight joints, a messenger-line carried by said marker-buoy and adapted to be housed within said receptacle, a sheave journaled within the receptacle around which said messenger-line operates, and means for locking said marker-buoy upon said receptacle, said means being operable from within the boat for releasing said marker-buoy.

4. An attachment for submarine boats, comprising a receptacle connected to the hull of the boat, said receptacle having an annular recess and a centrally disposed socket, a shoulder formed on the wall of said socket, a marker-buoy having a sleeve adapted to fit said annular recess and a central section adapted to fit within said socket, a messenger-line connected to said marker-buoy, said messenger-line being housed in the lower end of said annular recess and said socket when the marker-buoy is in position upon said receptacle, a sheave around which said line operates, means for locking said marker-buoy upon said receptacle, a hoisting cable having an anchor-bolt adapted to fit said socket when the marker-buoy is detached from said receptacle, and spring actuated pawls carried by said anchor-bolt adapted to engage said shoulder, said anchor-bolt being drawn into said socket by said messenger-line.

5. An attachment for submarine boats, comprising a cylindrical receptacle connected to the hull of the boat, a partition arranged in said receptacle, a centrally disposed tubular sleeve extending upwardly from said partition providing an annular recess and a central socket within said receptacle, a marker-buoy having a sleeve adapted to fit said annular recess and a central section adapted to fit within the sleeve of said receptacle, a messenger-line having its opposite ends attached to said buoy at different points and adapted to be coiled in

said recess and in said socket and held there-
in by the sleeve and central section of the
marker-buoy respectively against displace-
ment when said buoy is in position upon said
receptacle, a sheave journaled in said recep-
tacle around which said messenger-line op-
erates, and means for locking said marker-
buoy upon said receptacle.

In testimony whereof I have hereunto set
my hand this 24th day of August, A. D. 10
1914.

JOSEPH BARRAJA-FRAUENFELDER.
